INVENTOR.

Samuel M. Riker,

BY

Frazee & Richards, ATTORNEYS.

UNITED STATES PATENT OFFICE.

SAMUEL M. RIKER, OF CHESTER, NEW JERSEY.

BELT BUCKLE.

Application filed November 2, 1922. Serial No. 598,484.

To all whom it may concern:

Be it known that I, SAMUEL M. RIKER, a citizen of the United States, residing at Chester, in the county of Morris and State 5 of New Jersey, have invented certain new and useful Improvements in Belt Buckles; and I do hereby declare the following to be a full, clear, and exact description of the invention, such as will enable others skilled 10 in the art to which it appertains to make and use the same, reference being had to the accompanying drawings, and to characters of reference marked thereon, which form a part of this specification.

15 This invention relates to improvements in belt buckles; and the invention has reference, more particularly, to improvements in belt buckles of the pivoted clamp-jaw type, the said pivoted clamp-jaw means being of 20 such novel construction that it readily adjusts itself to both thick and thin belt bodies arranged operatively therewith, and to this end my invention provides a novel construction of clamp-jaw arranged in novel 25 relation to the pivoted loop-member from which the same springs.

The invention has for its principal object to provide in connection with a plate buckle body a novel construction of pivoted 30 loop member to which the fixed end of the belt body may be attached, said pivoted loop member having a novel construction of double clamp-jaw forming a part thereof which is adapted to clamp the free end 35 of the belt body by one or the other of its gripping or biting portions according to the thickness of said belt body.

40 Other objects of this invention, not at this time more particularly enumerated, will be clearly understood from the following detailed description of the same.

With the objects of this invention in view, the same consists, primarily, in the novel belt buckle hereinafter set forth; and, the 45 invention consists, furthermore, in the novel arrangements and combinations of the various devices and parts, as well as in the details of the construction of the said parts, all of which will be more fully described 50 in the following specification, and then finally embodied in the appended claim.

The invention is clearly illustrated in the accompanying drawings, in which:—

55 Figure 1 is a front face view of the novel belt buckle illustrating one embodiment of this invention, a belt body being shown op-

eratively attached thereto; Figure 2 is a side elevation of the same; Figure 3 is a rear face view of the novel buckle, the belt body being removed therefrom; Figure 4 is a 60 transverse section through the same, taken on line 4—4 in said Figure 3; Figure 5 is a central longitudinal vertical section on an enlarged scale through the novel buckle with belt body operatively attached there- 65 to and shown in side elevation, this view illustrating the operation of the novel clamp-jaw structure when engaging or gripping a comparatively thick belt body; and Figure 6 is a view similar to that shown 70 in Figure 5, but illustrating the operation of the novel clamp-jaw structure when engaging or gripping a comparatively thin belt body.

Similar characters of reference are em- 75 ployed in all of the above described views, to indicate corresponding parts.

Referring now to said drawings, the belt buckle shown therein comprises a main mem- 80 ber or buckle body consisting of a face plate 1, which is preferably outwardly convexed, and which is provided along its longitudinal edges with rearwardly projecting side flanges 2, and which is further provided with inwardly bent keeper flanges 3 spring 85 from the free edges of said side flanges to lie in a plane substantially parallel to and spaced rearwardly from the plane of said face-plate 1. Said side flanges 2 are pro- 90 vided at one of their ends with rearwardly projecting perforate ears or extensions 4.

The reference character 5 indicates the transverse base portion of a pivoted loop member from which extends outwardly be- 95 yond the adjacent end of the buckle body a loop portion 6. Projecting upwardly from the inner longitudinal edge of said base portion 5 is a primary clamp-jaw member 7. Projecting from the respective ends of 100 said primary clamp-jaw member 7, adjacent to the junction thereof with the base portion 5 are pivot studs or journal members 8, which are journaled in the perforate ears or extensions 4, to thereby pivotally connect said loop member with the buckle body. That portion of said primary clamp-jaw member 7 projecting above the pivotal connection of the loop member thus provided is inclined forwardly, and its free edge is 105 chamfered to provide the sharp biting or clamping edge 9 as shown. Connected with the outer longitudinal edge of said base por-

tion 5, intermediate the outwardly extending sides or arms 10 of said loop portion 6, is an upwardly projecting inwardly inclined secondary clamp-jaw member 11
5 which is parallel to but outwardly spaced or off-set from said primary clamp-jaw member 7. The free edge of said clamp-jaw member 11 is suitably chamfered to provide the sharp biting or clamping edge
10 12 as shown. The secondary clamp-jaw member 11 is somewhat shorter than the primary clamp-jaw member 7 so that normally the biting or clamping edge of the former lies in a slightly lower plane relative to the opposed bottom or inner surface of the face plate 1 than does the biting or clamping edge of the latter.

In attaching the belt body 13 to the buckle, one end 14 is looped and fastened
20 about the free end of said loop portion 6 so as to have a fixed relation thereto. In applying the belt and buckle to the waist of the wearer, the belt body 13 is caused to encircle the wearer's waist, and the free
25 end 15 of the belt body is inserted between the back of the face plate 1 and the keeper flanges 3 at one end of the buckle body, and is then passed between the back of the face-plate and the clamp jaw members 7
30 and 11 (the loop member being swung inwardly toward the body of the wearer to rotate said base-portion 5 thus swinging away from the back of the face-plate the said clamp jaw members so that the belt end
35 may be easily moved past said parts), and is then drawn up to tighten the belt body around the waist to the desired degree. When the belt body is thus adjusted about the wearer's waist, the tension to which the
40 same is adjusted tends to pull upon the loop member 6, swinging the latter in an outward direction to thereby turn or swing the clamp jaw-members toward the belt body 13 to pinch or clamp the same at a
45 point backed by the face-plate 1. If it happens that the belt body 13 is comparatively thick, the primary clamp jaw 7 will engage and grip the same, since its arc of movement about the pivotal point of swing
50 of the loop member is comparatively short (all of which is illustrated in Figure 5 of

the drawings), but if it happens that the belt body 13 is comparatively thin, so that the primary clamp-jaw member 7 does not effectively bite the same, then said primary 55 clamp-jaw member 7 tends to swing beyond the center or point of nearest approach to the face-plate, but the secondary clamp-jaw 11 by reason of its longer or greater arc of movement or swing will thereupon move 60 into gripping or biting relation to the comparatively thin belt body 13 (all as shown in Figure 6 of the drawings).

From the above description of the construction and operation of the buckle it will 65 be readily apparent that this invention provides a novel clamp element arrangement and structure which will readily accommodate itself to different thicknesses of belt bodies to which the buckle may be operatively connected.

Having thus described my invention, what I claim as new and desire to secure by Letters-Patent, is:—

A belt buckle comprising a face plate 75 having longitudinal side flanges, a clamp loop pivoted between said flanges adjacent to one end of said face plate and spaced rearwardly therefrom, said clamp loop having a base portion, a loop portion extending from said base portion beyond the adjacent end of said face plate, an inner clamp-jaw member extending normally toward said face-plate from the inner edge 80 of said base-portion, an outer clamp-jaw member of reduced height extending normally toward said face-plate from the outer edge of said base-portion, and pivotal means for said clamp-loop aligned with said inner clamp-jaw member whereby the arc of 85 movement of said inner clamp-jaw member toward said face plate is shorter than the arc of movement of said outer clamp-jaw member toward said face-plate.

In testimony that I claim the invention 95 set forth above I have hereunto set my hand this 24th day of October, 1922.

SAMUEL M. RIKER.
